CLAIM

The ornamental design for an overmolded housing for an interface cable, as shown and described.

DESCRIPTION

FIG. 1 is a perspective view showing a top, right, and front side of a preferred embodiment of our new design for an overmolded housing for an interface cable in accordance with the present invention;

FIG. 2 is a left side elevational view thereof;

FIG. 3 is a bottom plan view thereof; and,

FIG. 4 is a rear elevational view thereof.

The broken line showing throughout the drawing figures is included for the purpose of illustrating environmental structure only and forms no part of the claimed design.
